CARPET SWEEPER

Swift Miller, Milwaukee, Wis., assignor to E. R. Wagner Manufacturing Company, Milwaukee, Wis., a corporation of Wisconsin

Application July 31, 1936, Serial No. 93,549

4 Claims.

(Cl. 15—41)

This invention relates to an improvement in carpet sweepers.

One of the objects of the invention is to provide an improved stub axle mounting for floor wheels, that is, a mounting which enables the casing of the sweeper and consequently the brush thereof to be moved vertically relative to the floor wheels, thereby adapting the sweeper to be conveniently and effectively employed for heavy or light sweeping, as conditions may require. This action is had in a convenient and practical way and yet the floor wheels are always maintained in proper driving relation with the pulleys of the brush. Furthermore, the action is silent and the structure is such that it can be manufactured with facility and economy.

Another object of the invention is to provide improved means for floatably mounting the brush, thereby allowing the brush a certain freedom of vertical movement and also providing for the ready removal of the brush from the sweeper or its replacement therewith. Upward vertical movement of the brush is opposed by yieldable means such as light springs and the arrangement is such that ordinarily the bristles of the brush touch the top of the pile of a rug or carpet but by varying the pressure applied to the handle the brush is pressed into the pile to the extent required. In other words, the brush is, practically speaking, self adjusting, and the sweeping effect is varied, merely by varying the pressure on the handle.

Other objects and advantages reside in certain novel features of the construction, arrangement and combination of parts which will be herein-after more fully described and particularly pointed out in the appended claims, reference being had to the accompanying drawings, forming a part of this specification, and in which:

40. Figure 1 is a view in top plan showing a sweeper embodying the present invention, a part of the sweeper casing being broken away and shown in section for the sake of illustration;

45. Figure 2 is a view showing one type of stub axle mounting for the floor wheels, the view being in vertical section taken on line 2—2 of Figure 1, parts being broken away and parts being shown in dotted lines for the sake of illustration;

50. Figure 3 is a fragmentary sectional view taken on line 3—3 of Figure 1 and illustrating one type of brush mounting and also the brush pulley structure;

55. Figure 4 is a sectional view taken on line 4—4 of Figure 3 but illustrating the sweeper on a

reduced scale and further showing the brush mounting illustrated in Figure 3;

Figure 5 is a fragmentary view in section taken on line 5—5 of Figure 2 and further illustrating the stub axle mounting;

Figure 6 is a detail view in section taken on line 6—6 of Figure 2;

Figure 7 is a view in vertical section taken on line 1—1 of Figure 1 and illustrating the dust pans and brush combs;

Figure 8 is a fragmentary view in vertical section taken on line 8—8 of Figure 1 and showing the detachable connection between the handle and the socket of the sweeper ball;

Figures 9 and 10 are fragmentary sectional views taken on lines 9—9 and 10—10, respectively, of Figure 7 and showing the comb and dust pan mountings, respectively;

Figure 11 is a fragmentary view in bottom plan showing the portion of the metal casing of the sweeper in which an oval window is provided;

Figure 12 is a fragmentary sectional view taken on line 12—12 of Figure 11;

Figure 13 is a fragmentary view similar to Figure 2 but showing a modified form of stub axle mounting;

Figure 14 is a view in side elevation showing another sweeper structure embodying the present invention;

Figure 15 is a view in vertical section taken on line 15—15 of Figure 14;

Figure 16 is a fragmentary sectional view taken on line 16—16 of Figure 14;

Figure 17 is a fragmentary view taken on line 17—17 of Figure 15;

Figure 18 is a view in top plan of the structure shown in Figure 17;

Figure 19 is a fragmentary sectional view taken on line 19—19 of Figure 17;

Figure 20 is a detail sectional view taken on line 20—20 of Figure 13; and

Figure 21 is a view showing a modified form of the spring structure which acts on the floor wheels.

Referring to the drawings, and more particularly to Figures 1, 2 and 4, it will be seen that the sweeper comprises a casing designated generally at C and made up of a pair of wooden end plates 1 which are interfitting with notched ends of side rails 2. A curved metal casing member 3 50 of sheet metal is provided and at its front and rear is interfitting with rabbets 4 of the side rails 2. The ends of the sheet metal casing member 3 are flanged as at 5 and these flanges overlap the end walls 1. Each corner of the metal casing 55

member is fastened to the end plates 1 and side rails 2 and the side rails are fastened to the end plates by means of screws 6 (see Figure 1). This casing structure is very simple and yet highly effective and is also capable of very convenient assembly.

The case is completed in the form of the invention shown in Figures 1 to 7 by means of metal end plates 7 which are curved longitudinally and transversely and have inwardly directed flanges 8 on the opposite sides of cut-away portions or slots 9, the flanges abutting the flanges 5 and having lug-like extensions overlapping the side rails 2 and fastened thereto by screws 10. Screws 5' and 15 spacing sleeves 6' also aid in holding the metal end plates in proper position. A rubber bumper 11 encircles the sweeper casing and is releasably secured to the sweeper casing in any desired way.

The casing is supported by means of floor wheels 12. Four floor wheels are provided, there being a pair at each end in accordance with the conventional practice. Each floor wheel has a hub 13 which is rotatably supported on a stub axle 14. In the assembly the metal end plates 7 engage the rounded outer ends of the hubs 13 to prevent the floor wheels from being displaced from the ends of the stub axle. There is an individual stub axle for each floor wheel. Each axle is fastened at its inner end to a supporting arm 15. A bracket plate 16 is secured to each end wall 1 of the casing by means of screws 17. Each bracket plate 16 fits flush up against its end wall for the major portion of its extent. The bracket plate is centrally cut away in the same manner as the wooden end wall 1 of the sweeper casing to accommodate the brush and at each side has an outwardly displaced portion 18 which provides a socket or guide and also a stop structure for one of the arms 15. More specifically each bracket plate 16 is in the form of an inverted U-shaped stamping with the legs of the stamping straddling the notches in the end walls of the casing that accommodate the brush ends. The outwardly displaced portions 18 coat with the end walls to provide guides which constrain the arms 15 to vertical swinging and sliding movement. The upper and lower walls of the guides provide stops which limit the swinging movement of the arms. The portion of each arm 15 accommodated in its socket 18 is provided with a longitudinal slot 19 and a pin 20, which is fastened to the casing, extends through each slot 19 and limits the sliding movement of its arms as well as constrains it to pivoted movement. There is thus freedom for the arm to move a limited distance longitudinally and also to swing in a vertical plane. Usually the pins 20 are in the form of screws which not only provide the pin of the pin and slot connection but also aid in fastening the bracket plates to the end walls of the casing. A fiber washer 20' is mounted on each pin 20 between each supporting arm 15 and the adjacent end wall of the socket.

A spring 21 is provided for the two arms at each end of the sweeper. Each spring has a substantially straight and horizontal intermediate portion 22 which is, however, provided with V-shaped formations 23 which fit and anchor in spring seats 24 pressed out from the bracket plate. Each spring 21 has downwardly and inwardly inclined end portions 25 which are substantially straight and united with the intermediate portion 22 by integral bends 26. The extremities of the straight and downwardly inclined ends 25 are curved or curled as at 27 and are snugly fitted

in annular grooves provided on the arms by the outer end portions of the arms and by means of discs 28 fastened to the arms and to the stub axles in such manner as to provide these annular grooves. With springs so constructed there is a light or yielding resistance opposed to vertical movement of the casing relative to the floor wheels and yet the movement of the wheels laterally away from each other is opposed by a stiff and relatively heavy resistance. In this way the user of the sweeper may, by exerting pressure on its handle, correctly position the brush vertically for the height of the pile of the rug or carpet on which the sweeper is being used and yet the four wheels always have effective driving engagement with the brush pulleys.

When the springs 21 are assembled with their floor wheels and their seats 24, they are stretched somewhat out of their original shape and this brings into play their inherent resiliency whereby they properly bias the floor wheels and also hold the springs engaged with their seats 24. Any tendency of the springs to jump out of their seats is precluded in the assembly by the heads of the screws 17, which, when in place, block the entrance to the spring seats.

The shape and structure of the spring 21 may be varied in some respects. Thus, as shown in Figure 21 the ends may be reversely curled as indicated at 27' from the manner in which they are formed in Figure 2 to enhance their capacity for interlocking engagement with the annular grooves formed in the stub axle structure.

The rotary brush of the sweeper is designated generally at 30 and has shaft-like extensions 31 at its ends on which the brush driving pulleys, designated generally at 32, are secured. Each brush driving pulley 32 comprises an annular wooden body portion 33 suitably fixed to its shaft extension 31 and a metal casing or sheathing 34, the sheathing 34 being made of a single piece of sheet metal and having a portion 35 covering one face of the pulley, a portion 36 covering the periphery of the pulley, and a flange 37 which is spun or bent down over the other side face of the pulley to secure and hold the metal sheathing or casing in position. In the assembly the pulleys 32 are engaged with the floor wheels as illustrated in Figures 1 and 2 so that as the sweeper is propelled back and forth across the rug or carpet the floor wheels act on the pulleys 32 to rotate the brush.

In the ends of the shaft extensions 31 bearing sockets 38 are provided. Brush trunnions 39 are interfitting with the sockets 38 and provide the axis about which the brush rotates. These trunnions 39 are riveted or otherwise fixed to mounting strips designated generally at 40. In the form of the invention now being described and shown in Figures 1 to 7, the brush mounting strips 40 are supported for vertical sliding movement in guideways provided therefor in the metal end plates 7. These guideways are formed by displacing inwardly a lower portion of each metal plate 7, thus providing an outwardly facing groove 41. The upper portion of the metal end plates aligned with the guide grooves 41 are outwardly displaced to define an inwardly facing guide groove 42. Between the grooves 41 and 42 the end plates are slotted as at 43.

The upper portion of the mounting strips are provided with vertical guide slots 44. A headed pin or rivet 45 carried by each metal end plate 7 coacts with the slot 44 of its mounting strip to aid in constraining the mounting strip to vertical

sliding movement and also to limit the extent of its movement. The brush trunnions 38 which are riveted to the mounting strips project inwardly therefrom and extend through vertical slots 46 5 provided in each metal end plate 7. A spring 47 has its ends anchored under lugs 48 struck from the metal end plates and has its intermediate portion formed with a U-bend 49 and engaged over a headed stud or rivet 50 which is fixed to 10 the adjacent mounting strip. The spring 47 is tensioned to urge the mounting strips downwardly but may yield to permit the brush to move upwardly when operating conditions so require.

Dust pans designated at 51 and 52 are provided in the casing and are normally urged to closed position by a spring 53 although they may be swung to open position for dumping the contents thereof. The pivotal support for these pans is provided by headed pivot pins 54 which 20 are pressed or driven into and hence in effect countersunk in openings provided therefor in the wooden end walls 1 of the casing and are maintained in position by the bracket plate 16 which overlies them. This provides a very simple and 25 effective means for pivotally supporting the dust pans. Combs 55 and 56 coat with the brush in the usual manner and differ in their construction only in their pivotal mounting. As illustrated in Figures 7 and 9, each comb has at each end an 30 integral mounting lug 57. To this mounting lug a metal pivot pin 58 is riveted as at 59. The portions of the pins 58 projecting beyond the lugs 57 of the combs are fitted in bearing openings 60 provided therefor in the wooden end walls 1. It 35 has been found that by riveting metal pins to the combs and rotatably fitting them in holes in the wooden end walls, the action of the combs is improved especially in that they work far more silently than in previous structures. The usual 40 stop pins 61 are provided for the combs. Rubber sleeves 62 on the combs engage these stop pins to further silence the operation of the combs.

A handle 63 is provided for the sweeper and is connected to a socket 64 rigidly secured to a bail 45 65. The legs of the bail work in the slots 9 and the ends of these legs are inturned as at 66 and are rotatably interfitted with flanged bearings 67 provided in the bracket plates 16.

In order to releasably connect the handle 63 50 to its socket 64, the lower end of the handle is tapered as at 68. In this tapered portion 68 a spiral groove of uniform depth and designated at 69 is closed or cut. Threads 70 are provided on the socket 64 which, however, are of cylindrical 55 construction. With this arrangement the handle may be very firmly connected up to its socket and can be tightened up even after the parts have become worn, because of the wedging of the tapered lower end of the wooden handle in the cylindrical 60 socket.

An oval window 71 of Celluloid or other suitable transparent flexible material is provided in the metal section or cover 3 of the sweeper. This metal section or cover 3 has an opening formed 65 therein corresponding in outline to the outline of the window. The metal of the cover 3 around the margin of the opening is bent back upon itself as indicated at 73 in Figure 12. Integral with this bent back portion or flange 73 are clinching lugs 74 which, in the assembly, are bent around the edges of the window to firmly clamp the same 70 in position and retain it convexed or outwardly buckled.

In Figure 13 there is illustrated a slightly modified stub axle mounting for the floor wheels of the

sweeper. The casing is constructed as before and, as in the other embodiment, a bracket plate 75 corresponding to the bracket plates 16 is fastened to each end wall of the sweeper casing. In each side of the bracket a combined guide socket and 5 stop arrangement is provided as indicated at 76. An arm 77 has a pin and slot connection 78 with the bracket 75 and the sweeper wall 1. This arm carries the stub axle designated at 79. Pivoted 10 connected to the arm 77 by means of the stub axle 79 is a link 80. A spring 81 is anchored as at 82 to the bracket plate and has at each end 15 a downwardly and outwardly inclined straight portion 83 which has a loop 84 at its ends inter-engaged with a notch 85 provided in the outer 15 end of the link.

In the form of the invention shown in Figures 14 to 19, inclusive, the manner of supporting the brush and the construction of the metal end plates is varied. The metal end plates are substantially 20 devoid of the inwardly curved flanges corresponding to flanges 8 and 9 but have body portions 86 which parallel the end walls of the case and in-turned ends 87 which overlap and are fastened by screws 87' to the side rails of the wooden case. 25 The body portion 86 has its upper section inwardly depressed to provide a guideway 88 for the reception of a brush mounting strip 89. This mounting strip 89 is horizontally disposed and has reduced extensions 90 at its ends which extend through slots 30 91 provided in the body portion 86. The slots 91 are sufficiently long to allow the mounting strip the desirable vertical movement. The strips 89 are resilient and may be flexed outwardly to disengage their trunnions 92 from the bearings in 35 the ends of the brush shaft. In order to preclude accidental disengagement of the reduced ends from the slots 91 at such times, these extensions are preferably hook-shaped, as may be clearly seen in Figure 17.

A spring 93 is provided for urging the mounting strip 89 downwardly and against the shoulder 94 provided at the bottom of its guideway on the body portion 86 of the end plates. This spring has its intermediate portion anchored to its metal end plate by means of lugs 96, 97 and 98 struck from the metal of the end plate. The ends of the spring extend upwardly as at 99 and are hooked over the reduced extensions 90 of the mounting strip, as indicated at 100. Finger pieces 50 101 are provided in the center of each mounting strip to facilitate outward flexion thereof and also strengthen the portions of the mounting strips to which the trunnions are attached. The trunnions themselves may be riveted to the mounting 55 strips and the finger pieces 101.

From the foregoing it will be understood that the present invention provides a conveniently operable and efficient sweeper, one in which the character of the sweeping action is under the 60 complete control of the operator due to the manner in which the floor wheels are mounted and combined with their spring and with the brush. The brush mountings provide in effect a vertically floating or self adjustable brush without necessitating the manipulation of any adjustments but on the contrary responsive to the pressure applied to the handle. In connection with the responsiveness of the sweeper to pressure exerted on the handle by the operator, it should be 65 noted that the stop structure afforded by the upper walls of the sockets of the bracket plates 16 are engageable with the supporting arm 15 to positively prevent the casing from digging into the carpet. Another point to be observed in con- 70 75

- nection with the nature of the springs associated with the stub axles is that although the angle between the horizontal portion 22 of each spring and its downwardly and inwardly inclined end portions 25 may be varied this angle should hardly ever be greater than 45° if it is to have the dual capacity of ready yieldability to vertical pressure and yet force the floor wheels into proper driving engagement with the pulleys of the brush.
- 10 While I have shown and described several constructions in which the invention may be advantageously embodied, it is to be understood that these have been selected merely for the sake of illustration or example and that various changes 15 in the size, shape and arrangement of the parts may be made without departing from the spirit of the invention or the scope of the subjoined claims.

The invention claimed is:

- 20 1. A carpet sweeper of the character described comprising a casing, floor wheels therefor, individual floating stub axles on which the floor wheels are rotatably supported, individual supporting arms to which the stub axles are secured, 25 means supporting said arms for limited swinging movement in a vertical plane and for sliding movement fore and aft of the sweeper, a rotary brush disposed in said casing and having friction wheels engaged with and driven by said 30 floor wheels, spring means connected with said arms for opposing fore and aft movement thereof with a stiff resistance while presenting a relatively light resistance to vertical swinging movement of the arms, and a handle connected to the 35 sweeper casing.
2. A carpet sweeper of the character described comprising a casing having end walls, a bracket plate fastened flush against the outside of each end wall and having a pair of outwardly displaced portions providing guide sockets and stop structures, supporting arms slidably and swingably mounted in each of said sockets and projecting therefrom, the stop structures of said 40 sockets being engageable with the arms to limit the swinging movement thereof, a stub axle carried by the projecting portion of each of said arms, a floor wheel rotatably mounted on each of said stub axles, a rotary brush disposed in the casing and having friction wheels engaged with the floor wheels and frictionally driven thereby, 45 a spring at each end of the sweeper having a substantially horizontal portion fastened to the adjacent bracket plate, each of said springs being 50 the spring at each end of the sweeper having a substantially horizontal portion fastened to the adjacent bracket plate, each of said springs being

reversely bent at its ends and having straight downwardly and inwardly inclined end portions connected to the adjacent stub axles, and a handle connected to the sweeper.

3. A carpet sweeper of the character described 5 comprising a casing having end walls, a bracket plate fastened flush against the outside of each end wall and having a pair of outwardly displaced portions providing sockets and stop structures, supporting arms having portions fitted in the 10 guide sockets and portions projecting therefrom, pin and slot connections between the bracket plates and the portions of the supported arms fitted in said guide sockets, a stub axle carried by the projecting portion of each of said supporting arms, floor wheels rotatably mounted on the stub axles, a rotatable brush disposed within the sweeper casing and having friction wheels engaged with said floor wheels and driven thereby, and springs anchored to the bracket plates 20 and connected to the floor wheels and shaped and tensioned to maintain the floor wheels in driving engagement with the friction wheels while presenting relatively light resistance to vertical movement of the floor wheels relative to the 25 casing.

4. A carpet sweeper of the character described comprising a casing having end walls, a bracket plate fastened flush against the outside of each end wall and having a pair of outwardly displaced portions providing guide sockets and stop structures, supporting arms slidably and swingably mounted in each of said sockets and projecting therefrom, the stop structures of said 30 sockets being engageable with the arms to limit the swinging movement thereof, a stub axle carried by the projecting portion of each of said arms, a floor wheel rotatably mounted on each of said 35 stub axles, a rotary brush disposed in the casing and having friction wheels engaged with the floor wheels and frictionally driven thereby, a spring at each end of the sweeper having a substantially horizontal portion fastened to the adjacent bracket plate, each of said springs being 40 reversely bent at its ends and having straight downwardly and inwardly inclined end portions connected to the adjacent stub axles, and a handle connected to the sweeper, the horizontal portion of said spring having V-shaped formations, 45 said bracket plate having spring seats formed 50 therein in which said V-shaped formations are seated and secured.

SWIFT MILLER.
